R. H. JOHNSON

SPARK PLUG

Filed Feb. 12, 1923

Patented Mar. 18, 1924.

1,487,659

UNITED STATES PATENT OFFICE.

ROBERT H. JOHNSON, OF WASHINGTON, DISTRICT OF COLUMBIA.

SPARK PLUG.

Application filed February 12, 1923. Serial No. 618,605.

To all whom it may concern:

Be it known that I, ROBERT H. JOHNSON, a citizen of the United States, residing at Washington, in the District of Columbia, **5** have invented certain new and useful Improvements in Spark Plugs; and I do hereby declare the following to be a full, clear, and exact description of the invention, such as will enable others skilled in the art to **10** which it appertains to make and use the same.

The present invention relates to improvements in spark plugs and has for an object to provide an improved plug for use in internal combustion engines which will not foul with carbon and in which the current will be strengthened in order to provide a healthy spark at the gap with consequent economy in fuel and the development of **20** maximum power.

Other objects of the invention are to provide a plug which may be manufactured economically and sold at comparatively low cost on the market, to render the parts of the **25** plug easy to disassemble, thereby permitting of access to the core or insulator and to the spark gap and intensifier for the purpose of adjustment, repair and replacement of parts.

30 With the foregoing and other objects in view, the invention will be more fully described hereinafter, and will be more particularly pointed out in the claims appended hereto.

35 In the drawings, wherein like symbols refer to like or corresponding parts throughout the several views,

Figure 1 is a side view of an improved spark plug constructed according to the **40** present invention.

Figure 2 is a longitudinal section through the plug.

Figure 3 is a cross section taken on the line 3—3 in Figure 2.

45 Figure 4 is also a cross section taken on the line 4—4 in Figure 2.

Figure 5 is another cross section taken on the line 5—5 also in Figure 2, and

50 Figure 6 is a fragmentary section taken longitudinally through the lower portion of the plug showing the cleaning plunger in the raised position.

Referring more particularly to the drawings, 1 designates the shell having the **55** threaded shank 2 to enable it to be screwed into the head or cylinder of an internal

combustion engine in accordance with a well known manner. The upper portion of the shell 1 is made hexagonal as indicated at 3 to receive a wrench or other implement **60** for turning the shell. Within the shell is an internal shoulder 4 adapted to cooperate with a similar shoulder upon the lower section 5 of the insulator or core. The lower portion or stem of this section 5 is provided **65** with a cylindrical or other recess 6 opening upon the base of the core and adapted to receive a cleaning plunger which embraces the central positive electrode 7. This positive electrode extends down axially through **70** the recess 6 and slightly beneath the lower end of the porcelain where it forms a spark gap with the negative electrode 8, grounded upon the shell 2 and in this instance being carried by a side portion of the yoke 9 which **75** extends substantially diametrically from one side of the lower portion of the shell to the other, the yoke being curved in order to remove its intermediate part from interference with the electrodes or spark gap. **80**

A porcelain or other insulating pad 10 is carried by the intermediate part of the yoke 9 in position to act as a stop for the lower end of the cleaning plunger. This cleaning plunger is composed of a cylindrical barrel **85** 11 fitting the rod electrode 7 whereby to slide thereon freely back and forth. A flange 12 extends out radially from the upper end of the barrel 11 and a ring 13 is carried by the outer end of the flange, this ring **90** being arranged at right angles to the flange or concentric with the barrel 11. The ring fits the interior wall of the recess 6. The lower end of the barrel is slotted as indicated at 14 leaving teeth 15 between the **95** slots adapted to scrape the carbon from the electrodes and to permit passage of the spark through the slots 14.

The upper end of the positive electrode **100** 7 extends above the lower section 5 of the insulator and one or more radial arms 16, extending from the rod electrode are embedded in the porcelain to prevent creeping of the electrode axially which would disarrange the placing of the spark gap and the **105** intensifier gap. Of course the electrode can also be cemented in the porcelain.

Said upper end of the electrode 7 lies within a chamber 17 provided centrally of the lower part of the upper section 18 of **110** the insulator, which is also of porcelain or other non-conducting material. The lower

section 5 of the porcelain is provided with a marginal raised shoulder 19 which fits within a cut away portion 20 along the rim of the upper section, and a gasket 21 is interposed between the two meeting faces. A similar internal shoulder 22 projects downwardly from the upper insulator and cooperates with a recess 23 in the central portion of the lower section. A gasket 24 is interposed between these two meeting faces so the nut 25, which takes into the threads 26 on the shell may exert great pressure in forcing the insulator parts together and against the shoulder 4 in the shell without danger of injury or breakage in the core.

Now the chamber 17 is adapted to communicate with the atmosphere by one or more ports 27 arranged diagonally and extending from the upper portion of said chamber. The intensifier gap is thus permitted to "breathe." Into the upper portion of the chamber 17 projects an intermediate electrode 28 having a T-shaped head 29 embedded in the porcelain material and having the opposite branches of its head connected to the wires 30 and 31 which are arranged in the passage 32 extending down axially through the upper core section 18. In this core section is also disposed a magnet 33 or a strip of soft iron or other appropriate material being bent into the shape of a horse shoe and resting upon a supporting wall 34 of the insulating material which projects into the passage 32. The wires are wound a number of turns about opposite sides or poles of the soft iron bar and the magnetic flux or field set up will tend to retard the current or interpose a resistance which will intensify the spark leaping across the spark gap. The upper end of the wires are twisted together and arranged with the inverted T-head 35 upon the threaded binding post 36 which projects above the insulator and receives the binding nuts 37 and 38 by which the lead wire is coupled to the electrode.

In the use of the plug, the engine on its compression stroke will drive the cleaning plunger to the upper position shown in Figure 6, thus leaving the electrodes entirely free at the spark gap. When the circuit is closed at the end of the compression stroke, the spark reinforced by the magnet coils and by the intensifier gap, will leap across the electrodes serve to ignite thoroughly and completely the compressed charge. As the piston descends on its suction stroke, the cleaning plunger will be drawn down to the position indicated in Figure 2 and its movement will scrape any carbon deposits from the lower portion of the positive electrode and also keep any

carbon from bridging the spark gap. At the same time the ring 13 will scrape the walls of the recess and avoid the formation of carbon at this point so as to avoid short circuiting of the gap. The teeth 15 are peculiarly adapted for scraping the carbon and at the same time the slots 14 permit of the passage of the spark across the gap should the cleaning plunger for any reason be down when the current is turned through the plug.

Should the lower section 5 of the insulator become cracked because of the high temperature, or damaged for any other reason, the nut 25 may be removed and the sections of the insulator taken out of the shell and separated, the damaged section being discarded in favor of a fresh one. The cleaning plunger may be slipped off the electrode and inserted upon the electrode of the fresh section so that this part need not be replaced. In a similar manner if the upper section is injured. This may be replaced without requiring the expense of replacing the lower section and its parts.

It is obvious that various changes and modifications may be made in the details of construction and design of the above specifically described embodiment of this invention without departing from the spirit thereof, such changes and modifications being restricted only by the scope of the following claims:

What I claim is:

1. A spark plug comprising a shell, an insulator therein having a recess in its lower end, a positive electrode carried by the insulator and projecting through said recess, a negative electrode cooperating with said positive electrode and grounded on said shell, a plunger mounted to reciprocate in said recess and to scrape the carbon therefrom, said plunger also slidably fitted above the positive electrode and having slots at its base with teeth formed between the slots, and a yoke beneath the spark gap to arrest the movement of the plunger.

2. A spark plug comprising a shell, an insulator therein having a recess in its lower end, a positive electrode in the insulator extending into the recess, a negative electrode spaced at the side of the positive electrode, a plunger movably mounted in the recess and composed of a barrel sliding on the positive electrode, a flange on the upper end of the barrel, and a ring carried by the flange and wiping the wall of the recess, a yoke carried by the shell beneath the spark gap and having an insulating pad in the path of said barrel.

ROBERT H. JOHNSON.
